CLAIM

The ornamental design of a jug, as shown and described.

DESCRIPTION

FIG. 1 is a front elevational view of a jug according to the present invention and showing a carrying handle in a raised position.

FIG. 2 is a front elevational view of the jug and showing the handle in a lowered storage position.

FIG. 3 is a left side elevational view of the jug shown in FIG. 2, the right side view being substantially the same.

FIG. 4 is a top view of the jug as shown in FIG. 2; and, FIG. 5 is a bottom view of the jug shown in FIG. 2.
